UNITED STATES PATENT OFFICE.

LEON O. CORELL, OF KALAMAZOO, MICHIGAN.

CURRENT-CONTROLLING DEVICE.

1,052,891.

Specification of Letters Patent. Patented Feb. 11, 1913.

Application filed April 17, 1911. Serial No. 621,590.

To all whom it may concern:

Be it known that I, LEON O. CORELL, a citizen of the United States, residing at Kalamazoo, Michigan, have invented certain new and useful Improvements in Current-Controlling Devices, of which the following is a specification.

This invention relates to improvements in circuit controlling devices.

- 10 The main objects of this invention are: First; to provide an improved circuit controlling device for lamps or other circuits, which enables the opening or closing of the circuits from any desired number of points. 15 Second; to provide an improved controlling device for electrical circuits controlled by an electromagnet in which the circuit is closed on one energizing of the magnet and opened on the succeeding energizing of the 20 magnet. Third; to provide an improved control device for electrical circuits which enables the opening or closing of the circuits from a plurality of points with a minimum amount of wiring. Fourth; to provide an 25 improved device of the class described which is very compact in structure and not likely to get out of repair or to become inoperative. Fifth; to provide an improved control device of the class described which may be 30 operated by simple forms of control switches. Sixth; to provide an improved device of the class described in which the devices may be arranged and connected in series. Seventh; to provide in a device of the 35 class described an improved casing.

Further objects, and objects relating to structural details, will definitely appear from the detailed description to follow.

I accomplish the objects of my invention 40 by the devices and means described in the following specification.

The invention is clearly defined and pointed out in the claims.

A structure which is a preferred embodiment of my invention is clearly illustrated 45 in the accompanying drawing, forming a part of this specification, in which:

Figure I is a plan view of a structure embodying the features of my invention with 50 the cover removed. Fig. II is a detail view of a pair of the devices one being superimposed upon the other, the upper device being shown mainly in vertical section taken on a line corresponding to line 2—2 of Fig. I. 55 Fig. III is a vertical section taken on a line

corresponding to line 3—3 of Fig. I. Fig. IV is a perspective view of the armature and contact member 22 removed from the casing. Fig. V is an inverted perspective view of the control member 29. Fig. VI is 60 a diagrammatic view showing a series of the devices and their wiring.

In the drawings, similar reference characters refer to similar parts throughout the several views, and the sectional views are 65 taken looking in the direction of the little arrows at the ends of the section lines.

Referring to the drawing, 1 represents the casing and 2 the cover thereof. The casing is provided with flanges 3 on its bottom, so that when the casings are arranged in series as shown in Fig. II the superimposed casing serves as a cover for the casing below. The casing is provided at its upper end with cover engaging flanges 4. The 70 casing is preferably formed of porcelain, although other suitable insulating material might obviously be used. Or if desired the casing might be formed of any material and the parts arranged therein suitably insulated.

Within the casing I arrange an electromagnet 5. This is supported by the bracket 6 which in the structure illustrated is secured by the screw 7 arranged through the 85 bottom of the casing. The armature 8 is mounted on the pivot 9, carried by the bracket 10. This bracket is in the structure illustrated secured by the screw 11 arranged through the bottom of the casing. These 90 brackets are seated in the bottom of the casing as shown in Fig. II. Above the magnet I arrange a pair of circuit or terminal members 12, the rear wall of the casing being provided with seats 13 in which the members 12 are clamped by means of the screws 95 14 and the terminal members 16. The screws 14 are arranged in holes 15 provided therefor in the wall of the casing, to engage the terminal members 16. (See Fig. III). 100 At the rear of one of these seats the wall of the casing is provided with a vertical hole 17 through which the line wire 18 is passed. This wire is connected to the terminal member 16 by means of the binding screw 19. 105 When the devices are arranged in series as illustrated these holes 17 are in alinement and the line wire is extended through them all. The controlled circuit wire 20 is connected to the other terminal member as 110

22
shown in Fig. I. The wall is provided with a recess 22 for the wire 20.

Coacting with the circuit or terminal members 12 is a contact member 21, which is in the structure illustrated, mounted on the armature pivot 9 between the armature and the coils. With the parts in their open or normal position on the energizing of the magnet, the contact member 21 is closed. 5
10 On the succeeding energizing of the magnet the circuit is broken and the contact member returned to its open position. I will now describe the means by which this is accomplished.

15 The contact member 21 is provided with rearwardly projecting downwardly inclined flange-like keeper members 23, which when the contact member is closed are engaged by the offset like catches 24 on the ends of the circuit members 12, so that the contact member is retained in its closed position. The armature is provided with a release member 25, which is pivoted at 26 on the rearwardly projecting arm 27 on the upper end of the 20 armature. This release member is provided with a contact member catch 28. The arm 25 limits the downward movement of the release member on its pivot. A control member 29 is provided to coact with this release. 25
30 The rear end of this control member is arranged in a seat 30 provided therefor in the rear wall of the casing, its forward end resting upon the contact 21. At its forward end the control member 29 is provided with 35 flange like cams 31 which ride up on the contact member as it is closed, so that the control member is raised and retained in its raised or actuated position when the contact member is in its closed position. (See Fig. 40 III.) The control member is provided with stops 32 for the contact member and with 45 rests 33 at the rear ends of the cams 31. The flange-like cams 31 also serve as guides for the release member as it passes between them on the circuit opening actuation of the magnet. The control member is provided with a plate 34 of insulating material, which projects under the circuit members 12 so that when the control member is elevated 50 the forward ends of the circuit members are raised. When the control member is in its normal position as shown in Figs. I and II and the armature actuated, the release member 25 passes over the control member and 55 is thereby disengaged from the contact member, the contact member being engaged by the circuit members is retained in its closed position so that upon the deenergizing of the magnet the armature returns to its 60 initial position, leaving the contact member in its closed position. Upon the reenergizing of the magnet with the parts in this position, the control member is raised by the release member 25 as shown in Fig. III, to 65 break the circuit by separating the circuit

and contact members and the release member is engaged with the contact member so that on the deenergizing of the magnet the contact member is carried back to its open position. This completes the cycle of movement. It will be noted that the circuit is 70 broken upon the second energizing of the magnet. This is of advantage as it is very desirable to have it broken at this point rather than on the second deenergizing of 75 the magnet. Further a quick break of the circuit is secured, which prevents arcing. When the armature is in its open position, the rear flattened end 43 of the member 25 rests against the wall of the casing, which 80 holds the release member downwardly upon its supporting arm 27, as is shown in Fig. II.

The battery circuit wires 35 are connected to the magnet coils through the wires 36 which are arranged in passages 37 in the 85 walls of the casing and connected by the screws 38 to the terminal members 39. The switch wires 40 are arranged in similar passages. These passages open through the bottom of the casing for convenience in assembling parts with the connections. Thus arranged it is quite impossible for them to short circuit and the devices may be very 90 easily put into the system.

In Fig. VI I illustrate diagrammatically 95 a series of the devices, each device being provided with a pair of switches 41. These are shown in conventional form. It is obvious that they may be placed in any desired position. I illustrate a battery 42 as a 100 source of supply for operating the magnets. Any suitable source of supply may be used. This arrangement of parts reduces the amount of wiring to a minimum and the control switches may be of any form, a single push button switch serving to turn on or off the circuit, one closing of the switch will close the circuit controlled and the succeeding closing of the switch will open the circuit. 105

110 My improvements are especially designed by me for use in electric lighting systems, as they enable the control of the lamps from as many points as may be desired. The control switches 41 may be placed in any position for convenient manipulation and as a single switch or push button answers the purpose, the same can be placed in the floor or in any convenient position to be actuated by the foot as no selection of buttons for 115 opening or closing is required.

120 While the particular form illustrated has numerous advantages, I am aware that considerable variation in structural details are possible without departing from my invention, but as such variations will no doubt be readily understood by those skilled in the art to which this invention relates, I have not attempted to illustrate or describe the same herein.

Having thus described my invention, what I claim as new and desire to secure by Letters Patent is:

1. In a structure of the class described, the combination of an electromagnet; a pivotally supported armature adapted to swing away from said magnet when deënergized; a circuit member; a coacting contact member pivotally mounted between the armature and the magnet to be actuated by the armature; a release member pivoted on said armature and having a contact member catch; and a control member operatively associated with said circuit member and arranged to be engaged by said contact member, said control member being provided with a stop for said contact member and with downwardly-projecting flange-like cams with which said contact member coacts on closing to actuate said contact member and retain it in its actuated position, the forward end of said control member being forked to guide said release member, said cams also serving as guides for said release member which passes over said control member and disengages said catch from said contact member when the armature is actuated with the contact member in its open position, and under said control member and actuates the same to separate said circuit and contact members and to engage said catch with said contact when the armature is actuated with the contact member in its closed position.
2. In a structure of the class described, the combination of an electromagnet; a pivotally supported armature adapted to swing away from said magnet when deënergized; a circuit member; a coacting contact member pivotally mounted between the armature and the magnet to be actuated by the armature; a release member pivoted on said armature; and a coacting control member operatively associated with said circuit member and arranged to be engaged by said contact member and provided with cams with which said contact member coacts on closing to actuate and retain said control member in its actuated position, the forward end of said control member being forked to guide said release member, said cams also serving as guides for said release member which passes over said control member when the armature is actuated with the contact member in its open position, and under said control member and actuates the same to separate said circuit and contact members when the armature is actuated with the contact member in its closed position.
3. In a structure of the class described, the combination of an electromagnet; an armature pivoted at its lower end, said armature being adapted to swing away from said magnet when deënergized; spring circuit members; a coacting contact member pivotally mounted on the armature pivot between the armature and the magnet to be actuated by the armature, said contact member being provided with keepers at its upper end, said circuit members being provided with catches adapted to engage said keepers when said contact member is in its actuated position; a release member carried by said armature and having a contact member catch; and a coacting control member arranged to act on said circuit members, said control member being actuated by and retained in its actuated position by said contact member when it is actuated to circuit closing position, said release member passing over said control member upon the actuation of said armature when the contact member is in its unactuated position and disengaging the said catch from the contact members and passing under said control member and actuating the same to open said contact and circuit members and engage said catch with said contact member upon the actuation of said armature when the contact member is in its actuated position.
4. In a structure of the class described, the combination of an electromagnet; an armature pivoted at its lower end, said armature being adapted to swing away from said magnet when deënergized; spring circuit members; a coacting contact member pivotally mounted on the armature pivot between the armature and the magnet to be actuated by the armature, said contact member being provided with keepers at its upper end, said circuit members being provided with catches adapted to engage said keepers when said contact member is in its actuated position; a release member carried by said armature; and a coacting control member arranged to act on said circuit members, said control member being actuated by and retained in its actuated position by said contact member when it is actuated to circuit closing position, said release member passing over said control member upon the actuation of said armature when the contact member is in its open position and passing under said control member, and actuating the same to open said circuit and contact members upon the actuation of said armature when the contact member is in its closed position.
5. In a structure of the class described, the combination of an electromagnet; an armature; spring circuit members; a coacting contact member provided with rearwardly-projecting downwardly-inclined flange-like keepers at its upper end, said circuit members being provided with catches adapted to engage said keepers when said contact member is in its actuated position; a release member carried by said armature; and a coacting control member actuated by and retained in its actuated position by said contact member when said contact is in its

actuated position, said release member passing under said control member when said armature is actuated to disengage said contact member from said circuit members.

5 6. In a structure of the class described, the combination of an electromagnet; an armature; a circuit member; a release member carried by said armature and having a contact member catch; and a coacting control member actuated by and retained in its actuated position by said contact member, said release member passing over said control member and releasing said catch from said contact member upon the actuation of said 10 armature when the control member is in its unactuated position and passing under said control member and opening the circuit and engaging said catch with said contact member upon the actuation of said armature 15 20 when the contact member is in its actuated position.

7. In a structure of the class described, the combination of an electromagnet; an armature; a spring circuit member; a coacting pivoted contact member, said circuit and contact members being provided with coacting catch and keeper members; a release member carried by said armature provided with a contact member catch, and a coacting 25 control member operatively associated with said circuit member, and disengaging said catch from said contact member on the contact closing actuation of said armature, said release member actuating said control member to disengage the contact and circuit members on the succeeding actuation of said 30 armature and to engage said catch with said contact member.

8. In a structure of the class described, 40 the combination of an electromagnet; an armature; a circuit member; a coacting contact member; a release member carried by said armature, said release member being provided with a contact member catch; and 45 a control member for disengaging said catch from said contact member on the contact closing actuation of said armature, the closing of said contact actuating said control member, said release member, on the succeeding actuation of said armature actuating said control member to disengage said contact and circuit members and engaging said catch with said contact member.

9. In a structure of the class described, 55 the combination of an electromagnet; an armature; a circuit member; a coacting contact member actuated by said armature, a release member actuated by said armature, and a control member actuated and supported 60 in its actuated position by said contact member in which position said release member on the actuation of said armature actuates said control member to separate said contact and circuit members.

65 10. In a structure of the class described,

the combination of the electromagnet; an armature; a circuit member; a coacting contact member actuated by said armature; a release member carried by said armature provided with a contact member catch; and a 70 control member for releasing said catch from the contact member on the contact closing actuation of said armature, said control member being actuated by the closing of said contact member to permit said catch to 75 engage said contact member on the succeeding actuation of the armature.

11. In a structure of the class described, the combination of an electromagnet; an armature; a circuit member; a coacting 80 contact member actuated by said armature; a release member and contact catch carried by said armature; and a control member for releasing said catch from the contact member on one actuation of the armature, said 85 control member being actuated by the closing of said contact member to permit said catch to engage the contact member on the succeeding actuation of the armature whereby said contact member is returned to its inoperative position after such actuation.

12. In a structure of the class described, the combination of an electromagnet; an armature; a circuit member; a coacting contact member; an armature actuated member 95 engaging said contact member and separating said contact and circuit member to open the circuit on the energizing of the magnet and returning the contact member to its inoperative position on the deenergizing of 100 the magnet.

13. In a structure of the class described, the combination of an electromagnet; an armature; a circuit member; a coacting armature actuated contact member; a contact engaging and release member; a coacting control member operatively associated with said contact and circuit members and actuated by the closing of said contact member, said release member passing over said 105 control member on the contact closing actuation of the armature and under the same on the succeeding actuation of the armature to separate said circuit and contact members and to engage said contact whereby the circuit is broken on the energizing of the magnet and the contact returned to its inoperative position on the deenergizing of the magnet. 110 115

14. In a structure of the class described, 120 the combination of a casing of insulating material, having a cover flange and a bottom flange, the bottom flange being adapted to coact with the cover flange of another casing, whereby one casing may be superimposed 125 upon and serve as a cover for another, said casing being provided with a vertical circuit wire passage in its rear wall and with magnet circuit wire passages in its front wall, an electromagnet and an armature therefor ar- 130

ranged in said casing, supporting brackets for said magnet and armature seated in the bottom of said casing and secured by screws arranged through the casing bottom, the bottom being provided with seats for the heads of said screws, a contact member actuated by said armature, a pair of circuit members coacting with said contact member the rear wall of said casing being provided 5 with seats for said circuit members, circuit terminal members arranged in said seats and secured therein by clamping screws, the rear wall of the casing being provided with vertical holes for said screws open at the bottom, and magnet circuit terminal members seated in the front wall of said casing and secured by screws arranged in said magnet circuit wire passages, said passages being open through the bottom of the casing. 10 15. In a structure of the class described, the combination of a casing of insulating material, having a cover flange and a bottom flange, the bottom flange being adapted to coact with the cover flange of another casing, whereby one casing may be superimposed upon and serve as a cover for another, said casing being provided with a vertical circuit wire passage in its rear wall and with magnet circuit wire passages in its 20 front wall, an electromagnet and an armature therefor arranged in said casing, a contact member actuated by said armature, a pair of circuit members coacting with said contact member the rear wall of said casing 25 being provided with seats for said circuit members, circuit terminal members arranged in said seats and secured therein by clamping screws, the rear wall of the casing being provided with vertical holes for said screws 30 35 open at the bottom, and magnet circuit terminal members seated in the front wall of said casing and secured by screws arranged in said magnet circuit wire passages, said passages being open through the bottom of the casing. 40 45

16. In a structure of the class described, the combination of a casing of insulating material, having a cover flange and a bottom flange, the bottom flange being adapted to coat with the cover flange of another casing, whereby one casing may be superimposed upon and serve as a cover for another, said casing being provided with a vertical circuit wire passage in its rear wall and with magnet circuit wire passages in its front wall, an electromagnet and an armature therefor arranged in said casing, a contact member actuated by said armature, a pair of circuit members coacting with said contact member, and magnet circuit terminal members seated in the front wall of said casing and secured by screws

arranged in said magnet circuit wire passages, said passages being open through the bottom of the casing. 6

17. In a structure of the class described, the combination of a casing of insulating material, provided with a vertical circuit wire passage in its rear wall and with magnet circuit wire passages in its front wall, 70 an electromagnet and an armature therefor arranged in said casing, supporting brackets for said magnet and armature seated in the bottom of said casing and secured by screws arranged through the casing bottom, the 75 bottom being provided with seats for the heads of said screws, a contact member actuated by said armature, a pair of circuit members coacting with said contact member the rear wall of said casing being provided with seats for said circuit members, 80 circuit terminal members arranged in said seats and secured therein by clamping screws, the rear wall of the casing being provided with vertical holes for said screws 85 open at the bottom, and magnet circuit terminal members seated in the front wall of said casing and secured by screws arranged in openings through the bottom of the casing. 90

18. In a structure of the class described, the combination of a casing of insulating material, provided with a vertical circuit wire passage in its rear wall and with magnet circuit wire passages in its front wall, 95 an electromagnet and an armature therefor arranged in said casing, a contact member actuated by said armature, a pair of circuit members coacting with said contact member, and magnet circuit terminal members seated in the front wall of said casing and secured by screws arranged in openings 100 through the bottom of the casing.

19. In a structure of the class described, the combination of a casing of insulating material; an electromagnet and an armature therefor arranged in said casing, a contact member actuated by said armature, a pair of circuit members coacting with said contact member the rear wall of said casing being provided with seats for said circuit members and circuit terminal members arranged in said seats and secured therein by clamping screws, the rear wall of the casing being provided with vertical holes for said screws open at the bottom. 105 110 115

In witness whereof, I have hereunto set my hand and seal in the presence of two witnesses.
